UNITED STATES PATENT OFFICE.

JOSEPH W. DE CASTRO, OF NEWARK, NEW JERSEY.

EMERGENCY REPAIRER FOR BROKEN UMBRELLA-RIBS.

No. 830,307.

Specification of Letters Patent.

Patented Sept. 4, 1906.

Application filed December 4, 1905. Serial No. 290,310.

To all whom it may concern:

Be it known that I, JOSEPH W. DE CASTRO, of Newark, in the county of Essex, State of New Jersey, have invented a certain Improvement in Emergency Repairers for Broken Ribs of Umbrellas, of which the following is a specification.

My invention consists in an improved mode of repairing broken ribs of umbrellas in cases of emergency.

Figure 1 is a central sectional view of an umbrella-frame having my invention applied thereto; and Fig. 2 is a perspective view of one of my devices detached, showing the same as made of coiled wire.

My emergency repairer of broken ribs D and stretchers C of umbrellas consists of a tube F, made of metal or other suitable material, with a hook at one end and open at the other end, the hook to be passed under and around the wire in the niche A or under and around the wire in the runner B, from which the ribs D or the stretchers C are broken at the eye E, forming a hinge that holds the tube F loosely to the niche A or to the runner B, but securely.

The end of the rib D or the end of the stretcher C that is broken at the eye E is inserted into the open end of the tube F, in which it works loosely, but in connection with the cover of the umbrella will hold the rib D or the stretcher C in the positions they occupied before they were broken from the niche A or from the runner C and enable the

bearer of the umbrella to open or close, raise 35 or lower it for use the same as before the ribs D or the stretchers C were broken.

The emergency repairing-tube F can be attached to any part of the umbrella to remain until the emergency necessitating its 40 use arrives. It can then be adjusted in one or two minutes by the thumb and fingers without the use of tools.

I claim—

1. A device of the character described, 45 comprising a tubular body portion with an unobstructed opening at one end, and at the other end having a hook projecting from a point of the end edges of the walls of the body portion and lying in a substantially 50 diametric plane at the end of said tubular body and closing said end against the passage of an umbrella-rib.

2. A device of the character described, comprising a piece of wire coiled to form a 55 tubular body portion and having one end bent into a hook lying in front of the end opening of said tubular body portion and closing the same against the passage of an umbrella-rib, the other end of the body por- 60 tion presenting an unobstructed opening.

In testimony to my invention I here set my hand this 10th day of June, 1905.

JOSEPH W. DE CASTRO.
